UNITED STATES PATENT OFFICE.

ELIPHALET HALL, OF MORIAH, NEW YORK.

IMPROVED SMELTING-FURNACE.

Specification forming part of Letters Patent No. 42,470, dated April 23, 1864.

To all whom it may concern:

Be it known that I, ELIPHALET HALL, of Moriah, in the county of Essex and State of New York, have invented a new and Improved Smelting-Furnace; and I do hereby declare the following to be a full and exact description of the same, reference being had to the accompanying drawings, making part of this specification, in which—

Figure 1 is a plan of my improved furnace. Fig. 2 is a vertical longitudinal section in the line $x x$, Fig. 1. Fig. 3 is an elevation. Fig. 4 is a vertical section in the line $y y$, Fig. 1. Fig. 5 is a horizontal section in the line $z z$, Fig. 3. Fig. 6 is an elevation of the furnace proper. Fig. 7 is a horizontal section in the line $w w$, Fig. 6.

Similar letters of reference indicate corresponding parts in the several figures.

By the mechanical arrangement or combination of parts which constitutes the present invention means are provided whereby wood may be effectually employed as the heating medium in the process of smelting, it being impracticable to employ fuel of this character in smelting-furnaces constructed after the plans hitherto devised, by reason of the deleterious effect produced by the opening of the oven door or doors to supply fuel, which opening of the doors would of necessity have to be of frequent recurrence, in consequence of the rapidity with which the wood is consumed; hence coal, from its more substantial nature, has been almost exclusively made use of as fuel. My invention, besides obviating the above difficulty, admits of a most economical use of heat, and the advantageous employment of gas eliminated from the wood before the latter is deposited in the oven, all as will be hereinafter fully explained.

In order that others skilled in the art to which my invention appertains may be enabled to fully understand and use the same, I will proceed to describe its construction and operation.

In the accompanying drawings, A represents the smelting-furnace proper, in one end of which is located the fire-grate A'. The ore to be smelted may be introduced into the furnace through openings which are closed by the sliding doors $a a$, and the furnace may be supported at a sufficient height to allow molds to be placed beneath it, in order that the iron

will run off as extracted from the ore and be formed into pigs in customary manner.

a' represents a door which renders the grate accessible for the purpose of kindling the fire or removing the unconsumed products of combustion.

B represents a fuel department or oven, which occupies a position above the furnace A, and rests at one end upon the furnace A at a point directly over the fire-grate A', at which point the oven B communicates with the interior of the furnace through the throat B². The throat B² is opened or closed by a hinged door or valve, B³, which may be operated by a compound lever, B⁴, through the medium of a jointed rod, b, and link b'. Within the oven B is mounted an endless chain, C, which is provided with a continuous series of arms, c, between which is placed the wood to be deposited on the fire-grate A'.

The chain C is supported and turned or rotated by means of cast wheels C', which engage with the links in the manner shown, and which are keyed upon and revolved by shafts c' c', one of which protrudes through the side of the oven for the reception of a wrench, C², whereby the chain may be rotated, so as to cause its upper portion, upon which the wood is deposited, to move horizontally in the direction of the throat B². The arms c may be placed at such distance from each other that each space between the links will be sufficiently large to contain the requisite charge or quantity of wood to be supplied to the fire at proper intervals to maintain the desired degree of heat in the furnace.

To one end of the head of the compound lever B⁴ is jointed a rod, D, which connects with a link, D', the latter being adapted to rotate a pivoted shaft, D², which is pivoted in a fuel-box, D³, mounted on the oven B. In connection with the shaft D² is employed a door or valve, D⁴, which is opened by the turning of the lever B⁴, so as to deposit an additional supply of wood upon the chain C simultaneously with the opening of the hinged door B³ and the turning of the chain C, to supply the fire with a charge of fuel. Thus the upper portion of the chain C discharges a quantity of wood at one end and receives a supply at the other. The oven B is formed with additional interior walls, B⁵, between which and

the outer walls of the oven a sufficient space is left for the reception of escape heat from the furnace, as will be presently explained.

E represents the smoke pipe or stack of the furnace A, which rises from the top of the latter at one end, as illustrated. Leading into this stack, near the upper end thereof, is a pipe, E', which communicates with the space between the wall B⁵ and the outer walls of the oven B through an opening, E', Fig. 4. E³ represents a tuyere leading into the stack E at a suitable point below the juncture of the stack E and pipe E', and adapted to receive and direct a blast of air for the purpose of forcing into the pipe E' the escape heat which rises in the stack E, to insure the effectual accomplishment of which I employ a deflector, E⁴. The escape heat, being thus conducted into the pipe E', is thereby conducted into the space between the walls of the oven B, for the purpose of generating sufficient heat in said oven to bake or char the wood contained therein in such manner as to thoroughly dry the same and eliminate gas therefrom. Through the medium of a tuyere, F, this gas, together with the heated air from the stack E, may be forced by a blast of air into a pipe, F', whereby it is conducted into the furnace A, means being thus provided for saving all or nearly all the heat generated in the furnace and greatly promoting the smelting process. The pipe E' gradually increases in width toward its lower end, to equally distribute the heat and gas into the furnace. The apparatus admits of the escape heat being readily employed for getting up steam or any other desired purpose.

The walls B⁵, while permitting the requisite

heating of the interior of the oven B, prevent contact with the wood or anything from the smoke-stack E that might cause the wood to become ignited; and the oven B is designed to be constructed with suitable ventages, whereby the heat therein may be reduced when desired.

The bars of the fire-grate A' may, if desired, be formed of hollow cylinders, so as to constitute boilers to contain water for generating steam, and at the same time prevent injury to the grate-bars by contact with the fire.

Having thus described my invention, the following is what I claim as new therein and desire to secure by Letters Patent:

1. In combination with the furnace A, the fuel department or oven B, containing a feeding-chain, C, the whole being constructed and arranged to operate substantially in the manner herein set forth.
2. In combination with the oven B, constructed with double walls in the manner described, the pipe E' and tuyere E', adapted to be employed in connection with a blast of air to convey the escape heat to the oven B, for the purpose set forth.
3. Forcing into the smelting-furnace A the gas eliminated from the wood and the heated air conveyed from the stack E by the employment of the tuyere F and pipe F', substantially as and for the purposes explained.

The above specification of my improved smelting-furnace signed this 11th day of February, 1864.

ELIPHALET HALL.
